UNITED STATES PATENT OFFICE.

FRIEDRICH ZIEGENFUSS, OF BREDENEY, GERMANY, ASSIGNOR TO FRIED. KRUPP AKTIENGESELLSCHAFT, OF ESSEN-ON-THE-RUHR, GERMANY.

PARACHUTE FOR ILLUMINATING-BODIES.

1,319,553.

Specification of Letters Patent. Patented Oct. 21, 1919.

Application filed June 9, 1915, Serial No. 33,106. Renewed June 28, 1919. Serial No. 307,443.

To all whom it may concern:

Be it known that I, FRIEDRICH ZIEGENFUSS, residing at Bredeney, Germany, a citizen of the German Empire, have invented a certain new and useful Improvement in Parachutes for Illuminating-Bodies, of which the following is a specification.

The present invention relates to a parachute for illuminating bodies, which are 10 closed in a projectile, and shot out or liberated during the flight by means of a charge contained in the projectile.

One embodiment of the invention is illustrated in the accompanying drawing and

15 Figure 1 shows a side view of the unfolded parachute with the illuminating body and

Fig. 2, a portion of a top view of the unfolded parachute.

20 The carrying hood A of the parachute is composed of separate sector shaped pieces of strong linen material or the like. Where the linen pieces abut, the hood A is reinforced by sewn on strips a^1 of the same material. Similar reinforcements a^2 , a^3 , a^4 are also provided at the outer edge of the carrying hood, in its middle at a^3 and between the reinforcements a^2 and a^3 at a^4 . Through the strips a^1 a^2 a^3 a^4 are drawn

30 steel wire ropes B B^1 B^2 which are knotted together. The wire ropes B, which are drawn through the strips a^1 are extended and serve simultaneously for connecting the carrying hood A with the body C containing 35 the illuminating material to which the ropes are attached by means of a loop c^1 , see Fig. 1.

When the illuminating body is in the projectile, the parachute is compactly packed 40 in the projectile body. During the flight of the projectile, the illuminating material of the illuminating body becomes ignited and the parachute with the illuminating body shot out or liberated by a charge in the projectile. As soon as the illuminating body 45 has left the projectile housing, the air resistance acts on the parachute so that it will be unfolded and the illuminating body slowly descends to earth while its illuminating material is burning.

50 On account of the described construction of the wire ropes B B^1 B^2 the parachute possesses considerable strength. This circumstance is of the greatest importance, because 55 of the diminished speed of flight of the

illuminating body on the unfolding of the parachute, and quite considerable forces of inertia come into action, which tend to sever the connection between the parachute and the illuminating body. By this arrangement of the wire ropes is moreover attained that the parachute with certainty unfolds to the required shape, as the elasticity of the wire ropes comes into action, directly after the release of the parachute, which had been 60 compactly packed in the body of the projectile, thus causing the uniform swelling of the parachute.

I claim:—

1. A parachute for illuminating bodies 70 comprising a carrying hood, reinforcing elastic wires for the hood and supporting wires for suspending said illuminating body from said hood said reinforcing wires crossing each other at a plurality of places in the 75 hood.

2. A parachute for illuminating bodies comprising a carrying hood, reinforcing elastic metallic wires for the hood and supporting metallic wires for suspending said 80 illuminating body from said hood said reinforcing wires crossing each other at a plurality of places in the hood and being knotted at the intersections.

3. A parachute for illuminating bodies 85 comprising a carrying hood, reinforcing elastic wires for the hood and supporting wires for suspending said illuminating body from said hood, said supporting wires running radially from the center of the hood to 90 its edge, their free ends continuing from the edge of the illuminating body, said reinforcing wires and said supporting wires intersecting and running in and out through the material of the hood.

4. A parachute for illuminating bodies comprising a carrying hood, reinforcing elastic wires for the hood and supporting wires for suspending said illuminating body from said hood, said reinforcing wires 100 forming a plurality of concentric rings of different size running in and out through the material of the hood.

5. A parachute for illuminating bodies comprising a carrying hood, reinforcing 105 elastic wires for the hood and supporting wires for suspending said illuminating body from said hood, said reinforcing wires forming a plurality of concentric rings of different size running in and out through 110

the material of the hood, said supporting wires running radially from the center of the hood to its edge, their free ends continuing from the edge to the illuminating body, and said reinforcing and supporting wires being knotted at their intersections.

The foregoing specification signed at Barmen, Germany, this 19th day of May, 1915.

FRIEDRICH ZIEGENFUSS. [L. s.]

In presence of—

HELEN NUFER,

ALBERT NUFER.
